UNITED STATES PATENT OFFICE.

EDWIN HERBERT DAY, OF BENDIGO, VICTORIA, AUSTRALIA.

CLIPPING OR SHEARING APPARATUS.

1,128,765.

Specification of Letters Patent.

Patented Feb. 16, 1915.

Application filed July 28, 1914. Serial No. 853,767.

To all whom it may concern:

Be it known that I, EDWIN HERBERT DAY, a subject of the King of Great Britain and Ireland, &c., residing at Bendigo, in the 5 State of Victoria, Commonwealth of Australia, have invented certain new and useful Improvements in Clipping or Shearing Apparatus; and I do hereby declare the following to be a full, clear, and exact description of the invention, such as will enable others skilled in the art to which it 10 pertains to make and use the same.

This invention relates to durable clipping or shearing apparatus having a duplex reciprocating cutting device on a handpiece to be held to its work by one hand, as the right. This part, herein called the cutting tool, is provided with a non-rotating flexible member (as a wire of convenient length) 15 connecting it to a means of supplying power for the cutting tool consisting of a second tool which is to be held and operated by the other hand of the worker. This power device will be called the drive tool or the left 20 hand piece though it can be worked by either hand, and the cutting tool may be called the right handpiece, though it might be used in the left. Each tool can be moved independently of the other, within the 25 length of the connection. The flexible wire allows the cutting tool to be easily moved about, and as the hand holding the latter has only to locate it accurately, it is more able to do so than if the same hand had also 30 the labor of producing the reciprocating action.

The construction has time saving features and has no parts which rotate during clipping, and it is simple, and more convenient 40 in some respects than ordinary clippers. A barber's clipper does not allow of a person cutting his own hair, but I can cut my hair well and easily with my apparatus, though I have had no previous practice. Its use is 45 not restricted to human hair cutting.

Referring to the drawings herewith, which form part of this specification, Figure 1 represents a partly sectional view of my apparatus ready for use, with part of the flexible connection omitted, the cutting tool being in plan. Fig. 2 shows, partly in section, parts in Fig. 1 with the drive tool 50 handles pressed together, and the cutting tool in side view, with its cutter retracted. Fig. 3 illustrates the handle and comb of the cutting tool, in plan. Fig. 4 shows a

side elevation in vertical section of the cutting tool head. Fig. 5 shows a plan of the cutting tool with its parts in normal positions. Fig. 6 repeats Fig. 5, but with the 60 cutter retracted, and part of a tension spring omitted to show the comb end. Fig. 7 shows the cutting tool head in transverse vertical section, and Fig. 8 shows, in plan view, part of the under side of the said 65 head. Figs. 1 to 3 are on a smaller scale than the other views.

Designs, relative sizes, numbers, and minor details of various parts, may vary from what is illustrated while remaining 70 within the scope of my claims.

The drive tool has handle sides 1, 2, normally wide apart, and pivoted as at 3, but after being pressed near one another and released they resume their normal positions. 75 The said pressure pulls a flexible wire 7, 7^a, through a flexible casing 5, 5^a, 5^b, made of any suitable material such as spirally wound wire, the wire at 7 being connected as at 4 to a handle 2, part 5^a of the casing being 80 fixed or pinched in the handle 1 by means of screws 6, or the like suitable means. Any other drive tool however may be used with the cutting tool, so long as its action is to pull a flexible non-rotating connection. 85 Thus a power (instead of a manual) drive is feasible, as for animal clipping and shearing. The drawing omits to show the said casing at part 7^a of the wire. When a pull draws the wire longitudinally in the direction of the arrow in Fig. 1, it causes retraction of the cutter blade 18, to which the wire is connected by a rod 14 having at one end a suitable (as screw) connecting means 17, and at the other end a cap 13 which may 95 be set on the rod, and receive the end 5^c of the wire. Rod 14 on being retracted alters the tension of a spring device, as spiral spring 16 encircling the rod and located between an adjustable nut 15, which screws on 100 rod 14, and a stop member 12 located in the cutting tool handle 9. The comb 23 is affixed to handle 9 (which can have any convenient shape) as by screws 9^a. The respective toothed sides of the cutter are marked 105 18^a, 18^b; and of the comb 23^a, 23^b.

24 is a duplex hair length gage plate having toothed sides 24^a, 24^b. The comb alone will act as a gage when it is required to cut hair very short. If plates with similar sides 110 are used, a series of them would be provided and changed according to the lengths of

hair wanted, as each gage can be attached or detached easily, as by slide or screw devices, or a combination thereof. When pressure on handles 1, 2, is withdrawn, the spring 5 16 advances the nut 15 and thus rod 14 and cutter 18, to normal positions.

20 are studs or guide posts which project from the comb into central slots 19 which are in a longitudinal line in the cutter and 10 are of the length of the stroke of the cutter which, being thus guided, reciprocates across the comb to the extent of, for example, two teeth and their interspaces, when clipping is proceeding. Studs 20 are of 15 square or flat sided section to meet the slot sides and guide the cutter, and have screwed heads each to hold an adjustable nut 21 by which to locate part of a tension plate 22. A spring plate which bears on the cutter is 20 illustrated, middle pressure being suitable, but plates adapted for other locations of pressure are usable to produce the desired tension.

An aperture 10 in handle 9 would allow 25 of inspection and attention to a screw 9^a, but is mainly intended to allow adjustment of nut 15.

An anchoring member 8 is suitably fixed to handle 9 (which as drawn is of D-shaped 30 cross section with the flat side below) as by screws 10^a which are long enough (see Fig. 2) to fix the casing end 5^b against movement. This member or block 8 is at the rear of a space which I form by placing 35 any suitable distance member, as a tube 11, behind the washer or stop 12, through which the rod 14 passes.

As in Fig. 2 a single screw at 27^c, entering a hole in the gage plate just large 40 enough for it and put in by a turn screw is a simple arrangement usable, to fix securely in place the said gage plate. The end of a handle as 1^a is shown formed with an edge 45 adapted for inserting or removing the said screw.

Plate 24 in some cases may be made removable without using a tool. Thus it will be apertured or slotted at 27^c and 27 for parts of it to pass holding members 27^a, 27^b, 50 which may be screws set in position to hold the gage firmly. Or, as in Fig. 8, there is a slot 27 for engagement by screw 27^a, and a dovetailed arrangement of the comb and gage, as in Fig. 7. In Fig. 7 plate 24 has 55 sides of dissimilar thickness, side 24^a being the thicker, the intermediate under surface having any suitable form, a smooth slope 28 being illustrated. The length of hair left after the cut can be regulated according 60 ingly without altering the cutting tool.

Simultaneous double cutting can be avoided by holding the cutting tool appropriately, but it is at times more economical to make simultaneous or double cuts, and 65 with practice it is feasible by pushing the

cutter with its more thickly gaged side in front, in the direction of the arrow in Fig. 7.

I use a gage in some cases having teeth at only one side of the comb, the under side of the gage extending for example along 70 the dotted line to point 30 Fig. 7, as this would leave the comb on the other side to act as a gage for very short cutting.

The gage has blades which (see Fig. 8) are as thin as desired, and extend out beyond the comb teeth with which they register. The comb teeth extend as usual beyond the cutter teeth. The tops of the teeth of all the parts have an upward slope or the like, and those of the gage rise somewhat 80 higher than the comb teeth as at 31 in Fig. 7. This acts as a guide, to prevent hair or wool getting between the comb base and the gage top.

In my claims the word "duplex" means 85 that the part so called has two sets of teeth or is double sided, as distinguished from one sided combs, cutters and gages. Parts are so smoothed or rounded as to avoid unpleasantness to the subject to be clipped. 90

Having described this invention, what is claimed by Letters Patent is:—

1. In a clipper of the class described, the combination of a hollow handle, a comb mounted on the handle, a cutter slidably mounted on the comb, a rod connected to the cutter and extending through the hollow handle, a spring co-operating with the rod to operate the cutter in one direction, a flexible connection connected to the rod, 100 a pair of pivoted handles through one of which the flexible connection passes and to the other of said handles, said flexible connection is attached, whereby when the handles are squeezed together, the cutter will move in one direction; the aforesaid spring moving the cutter in the opposite direction. 105

2. In a clipper of the class described, the combination of a comb, a reciprocating cutter mounted on the comb and formed with slots, studs extending from the comb and through the slots, a tension plate engaging the studs and engaging the cutter, a handle extending from the comb, a flexible connection leading from the cutter, and means for reciprocating the cutter including a spring and a device for manually operating the flexible connection in opposition to the spring.

3. In a clipper of the class described, the combination of a stationary comb having lateral teeth, a cutter having laterally extended teeth operating above the comb, a gage located below the comb, said gage having laterally extended teeth which are reversely bent and terminate above the horizontal plane of the teeth of the comb.

4. In a clipper of the class described, the combination of a hollow handle, a comb mounted thereon, a cutter operating over 130

the comb, a second handle comprising a pair of levers, one of said levers pivoted to the other, a flexible connection a rod and a spring between the cutter and the pivoted lever, whereby to slide the cutter longitudinally over the comb in one direction, and means in the hollow handle for sliding the cutter in the opposite direction.

5. In a clipper of the class described, the combination of a comb, a cutter operating over the comb, a flexible connection for operating the cutter in one direction, a

spring for operating the cutter in the opposite direction, and a pair of handles pivoted together, and to one of which the flexible connection is attached, whereby to exert a pull on the flexible connection. 15

In witness whereof I have hereunto set my hand in the presence of two witnesses.

EDWIN HERBERT DAY.
